UNITED STATES PATENT OFFICE.

LAFAYETTE YOUNG, OF ALTON, ILLINOIS, ASSIGNOR TO LACLEDE STEEL COMPANY,
OF ST. LOUIS, MISSOURI, A CORPORATION OF MISSOURI.

REST BAR AND GUIDE BOX FOR METAL-ROLLING MILLS.

Application filed April 9, 1927. Serial No. 182 288.

This invention relates generally to improvements in mills of the type used in rolling metallic bars, and particularly to improved rest bars and guide boxes for this 5 type of mill, together with improved means for securing the guide boxes to the rest bars.

Prior to this invention guide boxes were secured to the associated rest bars by means of bolts and nuts, and as it frequently happens that the position of a guide box of a 10 mill must be shifted with great rapidity during the operation of the mill, it was found that much valuable time was wasted in unscrewing a number of nuts so that bolts could 15 be removed to permit movement of the guide box. This difficulty was increased by the fact that the nuts and bolts usually became corroded after a comparatively short time in use, and as a result the task of removing said nuts and the time required for such removal were materially increased.

The predominant object of the present invention is to produce rest bars and guide boxes which are so constructed that the guide 25 boxes may be secured to the rest bars in a manner to cause same to be very rigidly maintained in position and to permit of very rapid shifting of the positions of the guide boxes when desired, whereby the difficulties encountered 30 in the use of the fastening devices formerly used are eliminated.

Fig. I is a plan view of a fragment of a rest bar and a guide box constructed and secured together in accordance with my invention.

Fig. II is a cross section on the line II—II of Fig. I.

In the drawing, which embodies one form 40 of my invention, 1 designates a rest bar, a portion of which is broken away to conserve space, said rest bar being provided with a plurality of apertures 2 formed therethrough. The apertures 2 shown in the drawing are rectangular in shape, but it is obvious 45 that this particular shape need not be adhered to, as apertures of other shapes may be employed if desired. The rest bar 1 is provided with an upwardly extended portion 3 at one of its longitudinal edges which 50 extends from one end of the rest bar to the opposite end thereof, and the inner wall of said upwardly extended portion is arranged at an angle to the oppositely disposed wall of said portion to provide an inclined face 4.

Supported upon the rest bar 1 is a guide

box 5 which is provided with the ordinary guiding portion 6 having the usual elongated opening 7 formed therein. The guide box 5 is also provided with a downwardly extended portion 8 at its rear end, which portion is extended from one end of the guide box to the other end thereof. The forward wall of the downwardly extended portion 8 of the guide box 5 is arranged at an angle with respect to the rearmost wall of said portion to provide said portion with an inclined face 9 of approximately the same inclination as the inclined face 4 of the rest bar 1.

When the guide box 5 and the rest bar 70 1 are in assembled relation, the guide box is supported by the top face of the upwardly extended portion 3 of the rest bar and with the inclined face 9 of the downwardly extended portion 8 of the guide box in contact 75 with the inclined face 4 of the upwardly extended portion 3 of the rest bar 1, as shown clearly in Fig. II. With the parts arranged as described, a plurality of wedge-shaped members 10 are driven into certain of the 80 apertures 2 formed through the rest bar 1 to retain the guide box in position. Each of the wedge-shaped members 10 is provided with a straight face 10^a and a face 10^b which is arranged at an angle to said 85 face 10^a, and as a member 10 is driven downwardly into an aperture 2 the angular face 10^b which is being driven downwardly in contact with the wall of the aperture will force the guide box, the downwardly extended portion of which is in contact with the straight face 10^a of the member 10, forwardly so that the inclined face 4 of said 90 guide box will be in close contact with the inclined face 9 of the rest bar. The result 95 of this will be that the inclined faces 4 and 9 will be interlocked so that the guide box may not move upwardly without first being moved rearwardly, and the members 10, which are firmly driven into apertures 2, will 100 prevent this rearward movement.

By referring to Fig. II of the drawing it will be seen that each of the wedge-shaped members 10 is provided with an overhanging head portion 11, and when it is desired to disconnect the guide box from the rest bar to shift the position of said guide box it is only necessary that the outer end of a crowbar be introduced under the shoulders produced by the overhanging head portions of the wedge- 110

shaped members 10, and said members pried upwardly, thus permitting slight rearward movement of the guide box, whereby said guide box may be adjusted to the desired position on the rest bar and again secured in place, as already described.

While I have illustrated and described the rest bar and guide box arrangement intended for one side only of the rolls of the mill, I desire that it be understood that my invention is applicable to the rest bars and guide boxes employed at both the entry and discharge sides of the rolls.

I claim:

15. 1. A metal rolling mill comprising a rest bar provided with an aperture, a guide box, said rest bar and said guide box having overlapping portions adapted to prevent upward movement of said guide box relative to said rest bar, and a wedge-shaped member driven into said aperture in said rest bar in a manner to abut against said guide box and prevent disengagement of said overlapping portions, said aperture being disposed entirely below said guide box.

20. 2. A metal rolling mill comprising a rest bar provided with a plurality of spaced apertures, a guide box, said rest bar and said guide box having overlapping portions adapted to prevent upward movement of said guide box

relative to said rest bar, and wedge-shaped members driven into said apertures in said rest bar in a manner to abut against said guide box and prevent disengagement of said overlapping portions, said plurality of spaced apertures being disposed entirely below said guide box.

3. A metal rolling mill comprising a rest bar having a plurality of spaced apertures formed through a portion thereof and an upwardly extended portion provided with an inclined face, a guide box provided with a downwardly extended portion having an inclined face adapted to cooperate with the inclined face of said rest bar to prevent upward movement of said guide box relative to said rest bar, and wedge-shaped members driven into said apertures in said rest bar in a manner to abut against said guide box and prevent disengagement of said inclined faces, said wedge-shaped members having overhanging head portions adapted to facilitate easy removal of said members from said apertures, said plurality of apertures being disposed entirely below the downwardly extended portion of said guide box.

In testimony that I claim the foregoing I hereunto affix my signature.

LAFAYETTE YOUNG.
